UNITED STATES PATENT OFFICE.

STEPHEN F. BORKEY, OF FLINT, MICHIGAN.

AXLE-STRETCHING MACHINE.

1,299,292.

Specification of Letters Patent.

Patented Apr. 1, 1919.

Application filed February 28, 1918, Serial No. 219,560. Renewed February 20, 1919. Serial No. 276,287.

To all whom it may concern:

Be it known that I, STEPHEN F. BORKEY, a citizen of the United States of America, residing at Flint, in the county of Genesee 5 and State of Michigan, have invented certain new and useful Improvements in Axle-Stretching Machines, of which the following is a specification, reference being had therein to the accompanying drawings.

10 The invention relates to the manufacture of vehicle axles and more particularly to front axles or constructions designed for the mounting of steering-wheel spindles at opposite ends thereof. Such axles are usually formed by a process in which the opposite ends are successively refashioned by drop-forging. It is important that the axle should be of exact length, but it is difficult to secure such accuracy where the fashioning 15 of the ends is in successive operations. I have therefore devised an apparatus for securing absolute uniformity in length as hereinafter set forth and described. Another feature of the invention is the means 20 for re-fashioning the spring pads of the axle simultaneously with the operation for securing accuracy in length.

In the drawings:

Figure 1 is a plan view of the machine for 25 operating upon the axle;

Fig. 2 is a side elevation thereof partly in section;

Fig. 3 is an end view thereof partly in section.

30 Axles of the character described usually are formed with a central section A which is of an I-beam or other structural shape. At opposite ends of this central beam section are bifurcated portions B and B' which 35 form the bearings for the axle spindles, and spring-pads C and C' are formed on the upper face of the beam adjacent to the bifurcated ends thereof. Broadly described, the opposite ends of the axle are fashioned 40 to the desired form without attempting to secure exact uniformity in length, but with the central beam portion shorter than in the finished product. My improved apparatus stretches the central portion of the structure 45 thus formed so that the fashioned end portions are brought into exact relative positions.

In forging the bifurcated end portions of the axle, the spring pads are simultaneously 50 fashioned, but for convenience they are

made symmetrical on opposite sides of the axle beam. This is not, however, the shape which is desired in the finished product, as the pad should be tilted with respect to the central plane of the beam and given a 60 slightly concave form on its upper face, which shape would be difficult to form by the drop-forging process. I therefore provide means for refashioning the same and imparting thereto the desired contour at the 65 same time that the axle beam is stretched.

My improved construction is as follows: A' is the bed of a press which has mounted thereon the shaft B² carrying the cranks C² connected by pitman-rods D with a sliding 70 cross-head E. F is a work holder extending transversely of the bed and bearing against an abutment G thereon which is opposed to the movement of the sliding head E. This work-holder includes a stationary, 75 transversely-extending guide and a pair of clamping heads H slideable upon said guide and engageable with the axle. As specifically shown, these clamping heads have upper and lower die-members I and J for embracing the beam adjacent to the pads, a clamping-lever K having a cam L for bearing on the upper die and a hinged or pivoted member M for said lever and cam 80 rockable to a position permitting the engagement and disengagement of the work, and in operating position connected to the lower die-member by a link N. The arrangement is such that the axle may be disengaged from the upper and lower die-members I and J when the lever K is in the position K', Fig. 2, and by then rocking said lever and mounting M to the position shown at K² the link L may be engaged with a pin L', coupling the same to the lower die-member. The lever K may then be rocked upon its mounting M so as to cause the cam 85 L to clamp the upper die-member I upon the work.

Each of the clamping heads H is preferably provided with an anti-friction roll O, which is in the path of a cam member P carried by the sliding head E. This cam member P has a tapering end portion P' for passing between the rolls O and for then forcing them in opposite directions, thereby effecting a sliding movement of the heads H. As these heads when clamped to the roll are adjacent to the spring-pads C and C', the latter will act as stops or shoulders, and there- 100 105 110

fore as soon as these shoulders contact with the heads H any further movement of said heads must necessarily stretch the axle.

- The cam P is preferably bifurcated, the 5 furcations thereof passing above and below the axle and engaging with pairs of rolls O so as to exert a stretching force symmetrically with respect to the longitudinal axis of the axle. On opposite sides of the cams 10 P are forming dies Q which contact with the pads C and C' simultaneously with or immediately succeeding the stretching operation. These forming dies, as shown are of a shape to re-fashion the axle pads, 15 parting thereto the desired tilt and cavity.

In operation, the axles which have been first formed of variable length between the opposite end portions thereof are brought 20 to size by heating to the proper temperature and then placing in the machine, as has been described. When motion is imparted to the cross-head through the medium of the pitmen D and crank C² the bifurcated cams P will first engage the rolls O and force the clamping heads H upon the transverse guide F in opposite directions. These clamping heads will slide upon the axle until the shoulders formed by the pads 25 30 C and C' come into contact with the cooperating bearings on the clamps, after which the axle is stretched until the clamps are forced to the limits of their respective movements. It will be understood that the pads C and C' are always in exactly predetermined relation to the bifurcated ends of the axle, as they are formed in the same operation and by the same dies. Consequently, whatever the original length of 35 40 the axle may be, after this stretching operation there will be an exact dimension between the bifurcated ends; also the pads will be re-fashioned to the proper contour.

What I claim as my invention is:

- 45 1. An axle-stretching machine, comprising a bed, work-engaging members, one of said members being movable transversely of said bed, and means movable longitudinally of said bed for actuating said movable member away from said other member

to effect the stretching of the portion of work therebetween.

2. An axle-stretching machine, comprising a bed, work-engaging clamps transversely movable of said bed, a head movable longitudinally of said bed, and means carried by said head for spreading said clamps in opposite directions to stretch the portion of the axle therebetween.

3. An axle-stretching machine, comprising a bed, a guide extending transversely thereof, work-engaging clamps slidable upon said guide, a movable head, and means carried by said movable head for spreading said clamps in opposite directions to effect 60 the stretching of the portion of the work therebetween.

4. An axle-stretching machine, comprising a bed, a stationary guide extending transversely thereof, heads slidable upon 70 said guide, work-clamps upon said heads for engaging the fashioned end portions of the work, a head movable longitudinally of the bed, and a cam on said head for engaging said sliding heads to spread the same and to 75 stretch the portion of the axle therebetween.

5. In an axle-stretching machine, the combination with a bed, of a guide extending transversely thereof, heads slidable upon said guide, clamps on said heads for engaging the work, including a portion for engaging the axle-pads, a head slidable longitudinally of said bed, means carried by said head for engaging said transversely-slidable heads and spreading the same, and 80 dies also mounted on said longitudinally-movable head for engaging said axle-pads and refashioning the same.

6. In an axle-stretching machine, the combination with a bed, of heads movable transversely thereof, clamps on said heads for engaging the work, rolls upon said heads, a head slidable longitudinally of said bed, and a bifurcated cam member upon said last mentioned head for engaging said rolls 90 to spread said transversely movable heads in opposite directions.

In testimony whereof I affix my signature.

STEPHEN F. BORKEY.
